CAR TOP CAMPER

Jimmy M. Lambert, 2108 Stonebridge Road,
Dothan, Ga. 36301

Filed May 20, 1970, Ser. No. 23,065

Term of patent 14 years

Int. Cl. D12—16

U.S. Cl. D14—27

FIG. 1

FIG. 2

FIG. 3

FIG. 1 is a perspective view showing the rear and one side of a car top camper embodying my new design, the car and support brackets being shown in broken lines for illustrative purposes only.

FIG. 2 is a view showing the front and the opposite sides, adjacent to the car, opened for use as though attached to a car.

FIG. 3 shows the hinged-hardtop section closed on its floor.

I claim:

The ornamental design for a car top camper, substantially as shown and described.
